 Gwendoline Bruneau(57) **CLAIM**

The ornamental design for a flip top cap, as shown and described.

DESCRIPTION

FIG. 1 is a top perspective view of the flip top cap;
 FIG. 2 a top view of the flip top cap of FIG. 1;
 FIG. 3 is a side of the flip top cap of FIG. 1;
 FIG. 4 is a side view of the flip top cap of FIG. 1;
 FIG. 5 is a front view of the flip top cap of FIG. 1;
 FIG. 6 is a rear view of the flip top cap of FIG. 1; and,
 FIG. 7 is a bottom view of the flip top cap of FIG. 1.
 The broken lines shown illustrate portions of the flip top cap
 that form no part of the design.
